CUPOLA FURNACE

Application filed February 7, 1928. Serial No. 252,506.

Reference is had to the accompanying drawings which illustrate the preferred form of the invention; though it is to be understood that the invention is not limited to the exact details of construction shown and described, as it is obvious that various modifications thereof within the scope of the claims will occur to persons skilled in the art.

In the drawings:

10 Fig. 1 is a sectional view through the cupola of the present invention;

Fig. 2 is a fragmentary detail sectional view through a portion of the cupola, the view being taken on the line 2—2 of Fig. 3;

15 Fig. 3 is a view, partly in section, on the line 3—3 of Fig. 2;

Fig. 4 is a fragmentary front elevation of two sections of the supporting ring used in the invention and shown in section in Fig. 2;

20 Fig. 5 is a detail sectional view through a portion of the cupola, showing a modification of the specific mounting means for the rings forming a part of the cupola;

Fig. 6 is a sectional view showing a segmental form of ring;

Fig. 7 is a fragmentary front view of the particular type of segmental ring shown in Fig. 6;

Fig. 8 is a fragmentary front view of the 30 assembled rings;

Figs. 9 to 13, inclusive, are detail sectional views showing various means of connecting the superimposed rings shown in Fig. 8;

Fig. 14 is a diagrammatic sectional view of 35 the cupola of the present invention showing the alternate coke and ore beds; and

Fig. 15 is a fragmentary sectional view showing a modification of the supporting means for the lowermost ring.

40 This invention relates to cupola furnaces for use in the smelting and reduction of ores generally.

One of the objects of the present invention 45 is the provision of a cupola of novel design and construction which will effect great economy in fuel.

Another object of the invention is the provision of a cupola wherein the gas producer effect is reduced beyond that generally in ex-

istence in connection with the operation of the usual cupola.

A further object of the invention is the provision of a hot blast cupola in which the air is preheated in a zone above the combustion zone whereby to reduce the temperature in the furnace above the combustion zone and prevent the absorption of carbon by the CO_2 to thereby reduce the gas producer effect of the cupola. 55

A still further object of the invention is the provision of a cupola having means for reducing the temperature in the shaft of the cupola above the combustion zone whereby to retain the fuel beds therein at a cooler temperature, more particularly a temperature such that a large number of the heat units of the fuel will be preserved or retained in the fuel prior to the delivery thereof to the combustion or melting zone of the cupola. 60

Another object of the invention is the provision of a novel design of cupola, the interior or shaft of which is of successively decreasing diameter from a point above the melting zone to the top of the furnace whereby to aid in retarding discharge of the productions of combustion, thereby obtaining complete combustion of the fuel in the melting zone of the cupola. 70

The invention also contemplates the substitution of a metallic lining or liner for a portion of the usual refractory lining; the metallic lining serving to define in conjunction with the outer casing or sheathing of the furnace, a heating chamber for air which will absorb or take from said metallic lining the heat thereof, thereby permitting said metallic lining to absorb more heat from the shaft of the furnace and thus reduce the temperature in said shaft above the combustion zone of the cupola to retain the fuel beds in this portion of the furnace at a reduced temperature, or a temperature below that normally found in the customary cupola of today. 80

The usual cupola, as is well known, has a gas producer effect and the fuel layers in the shaft of the cupola are subject to intense heat from the moment they are introduced into the upper section of the cupola, which temperature gradually increases until the fuel beds 95 100

reach the melting zone. It is apparent that due to the heat to which the fuel beds or layers are subjected a large number of the heat units present in the fuel are lost prior to the utilization of the fuel in the combustion or melting zone. These heat units go off as waste gases and are usually a total loss.

It is the aim of the present invention to conserve these heat units in the fuel layers until they reach the melting zone of the furnace, and it has been found that by reducing the temperature in the shaft of the cupola above the melting zone the heat units are preserved in the fuel until they reach the combustion zone. Actual tests have been made of the furnace shown in the present application, and great economy in fuel has been obtained. It has been found that when the temperature of the combustion gases in the furnace is high, the coke charge required is proportionately high and it has further been found that when the temperature of the combustion gases in the furnace shaft above the melting zone is reduced, the coke charge necessary for efficient operation of the furnace is proportionately reduced, and as the temperature of the combustion gases in the shaft of the furnace above the melting zone is further and further reduced, it is obvious that still lesser amounts of fuel are required. This, it is believed, is due to the particular construction and operation of the furnace of the present invention, which is specifically described hereafter.

The furnace of the present invention comprises a construction having, in effect, separate zones, namely, a melting or combustion zone, a preheating zone just above the melting zone in which the fuel and ore or other material are preheated prior to their entrance into the melting zone, and a magazine above the preheating zone into which the layers of fuel and ore are charged and where such layers are maintained at a temperature below that present in the usual cupola or furnace whereby to prevent the loss of heat units in the fuel. This magazine might properly be termed a cool zone, in contradistinction to the corresponding zone in the cupolas now in present day use.

In addition to the objects specified above, various other objects and advantages of the invention will be apparent to those skilled in the art from the following description taken with the accompanying drawings in which, referring specifically to Fig. 1, 2 designates the outer casing or sheathing of a cupola which is mounted on a suitable base 4, and is provided with charging doors 6 or a chute 8 for the same purpose; the interior of the casing 2 being provided at its lower portion with a refractory lining 10 which extends upwardly somewhat above the usual melting zone of the cupola.

The casing 2 is formed of sections 12 and

14 which are secured together in any suitable manner and may be so secured as to permit expansion and contraction thereof if desired.

In carrying out this invention, I substitute for the refractory lining, which is usually continuous from the base to the top of the furnace, a lining indicated generally at A spaced from the casing 2 and formed preferably of a plurality of superimposed metallic sections B provided with radially extending external fins or corrugations 24, each of which is continuous around the sections; the sections being securely but detachably connected together as hereafter described. The several sections forming the lining B are in the form of rings and for clarity they have been designated as 26, 28 and 30, respectively, the rings each being provided with internal vertical corrugations or ribs 32.

Referring particularly to Figs. 1, 2 and 5, it can be seen that the upper inner edge of the refractory lining 10 is cut away to receive the depending lower edge of the lowermost ring 26, the ring being provided with a laterally extending supporting flange 34 which seats upon and is supported by the horizontal leg 36 of a supporting angle indicated generally at C.

The ring C is composed of a plurality of arcuate segments and, referring to Fig. 2, each thereof includes a vertical leg 38 and the before-mentioned horizontal leg 36; the vertical leg being secured to the casing 2 by means of bolts 40. The refractory lining 10, more particularly the upper surface thereof, is provided with an annular recess in which the horizontal leg of the supporting ring is seated, the latter extending to a rib 42 defined by the recess and by the cut away portion of the inner edge of the lining. Obviously, the segments of the supporting ring are angle segments, the same being arcuate in form, and at each end thereof said segments are provided with webs 44 which abut each other when the sections are assembled, as clearly shown in Fig. 3, the assembled segments defining the supporting ring heretofore mentioned with the webs extending from the vertical legs 38 of the angles to the horizontal legs 36. The horizontal legs 36 extend to and preferably contact with the rib 46 of the refractory lining 10, and tie rods 48 are used to connect the several superimposed sections, the lower ends of the tie rods extending through the flange 34 of the ring 26 and through the horizontal leg 36; suitable nuts 50 being employed for securing the tie rods in position in an obvious manner.

Fig. 4 discloses a detail view of adjacent angle segments, and it can be seen in said figure that each angle is provided at one end with a depending supporting lug 52 upon which is seated the end of the next adjacent angle.

Fig. 5 shows a slightly different type of connection, although the construction of the lower end of the ring 26 is identical with that shown in Fig. 2, the same having the lower extension and the lateral supporting flange 34. The angles which make up the supporting ring shown in Fig. 5 are shown as being formed with a horizontal supporting leg 54 which extends to the rib 42 and with a depending leg 56 secured to the lower sheathing section by means of bolts 58. As shown in this figure, tie rods 48 are also provided which extend through the supporting flange of the ring 26 and the horizontal leg of the supporting ring and have securing nuts 50 at the lower ends thereof for an obvious purpose.

The rings 24, 26 and 28, as clearly shown, overlap each other; the rings 26 and 28 overlappingly engaging at their lower ends the rings 24 and 26 respectively, this construction being designed in order that there will be no lodging of particles of either ore or fuel in any of the abutting or meeting surfaces within the shaft of the furnace, as will be apparent.

The metallic lining B is, as shown, spaced from the sheathing of the furnace, and defines with said sheathing a heating chamber indicated generally at D which is divided into a plurality of sections (three, in the present instance) by means of baffles 60 supported by the rings at the juncture of adjacent or superimposed rings. The baffles extend to the casing or sheathing 2, and if desired may be secured to the latter in any suitable manner. Adjacent the ring 26 an air intake 62 is provided, and the baffles 60 are provided with oppositely arranged openings 64 to permit air to pass through the heating chamber sections in a zigzag or circular path to a conduit 66 connected to the air belt conduit or wind box 68 surrounding the outside of the furnace and registering with the tuyères 70 therein. The fins have been described as extending laterally from the rings 26, 28 and 30, but it is to be understood that within the spirit and scope of the invention each ring may be provided with a continuous spiral fin, if desired, whereby to impart a cyclonic effect or movement to the air admitted through the intake to the heating chamber. The uppermost ring 30 is provided with a laterally extending flange 74 which bears against a sealing plate 76 supported by an angle 78 secured to the casing 2, and the upper ends of the tie rods extend through the flange 74 and through the plate 76 and are locked by means of wedging keys 80 in an obvious manner. The upper edge of the ring 30 supports a metallic ring 82, which I term a "false ring", the latter extending to a closing plate 84 and being secured thereto, if desired, in any suitable manner.

As before-mentioned, the rings 26, 28 and 30 are internally corrugated and externally ribbed, the external ribs being of substantial

size whereby to provide as wide a contacting area for the air in the heating chamber as is possible. If desired the rings 26, 28 and 30 may be provided with external vertical ribs in lieu of the laterally extending ribs, the ribs, whatever may be the arrangement, serving as heat radiating surfaces and also as strengthening elements.

The description just above pertains generally to the cupola of the present invention, and the specific details will be fully described hereinafter. It is deemed advisable at this time, however, to briefly set forth the operation of the cupola, and, referring to Fig. 1 and also to the diagrammatic Fig. 14, it can be seen that, as is usual, alternate layers of fuel such as coke or the like and ore are charged in the shaft of the furnace, the layers of fuel and ore being designated as 86 and 88, respectively in Fig. 14. The combustion or melting zone of the furnace is, of course, just adjacent the tuyères. The ordinary cupola heats the fuel the entire length of the shaft and, indeed, takes from the fuel a large number of heat units thereof prior to its reaching the melting zone. In the furnace of the present invention it can be seen that air entering the lower section of the heating chamber through the air intake strikes the ribs or fins of the ring 26 and is heated, taking the heat from the ring. In a furnace of usual construction—that is, one in which the refractory lining extends the full length of the shaft—said lining takes the heat from the shaft but retains it, thereby maintaining an intense heat in the entire shaft of the furnace; no means being provided for taking this heat from the refractory lining and permitting the lining to take up more heat from the shaft of the furnace to reduce the temperature therein. The furnace of the present invention provides a metallic lining which is formed of a special kind of metal, the particular metal, however, forming no part of the present invention in detail and therefore not being definitely stated, as obviously many kinds of metal may be employed which will have the characteristics necessary in carrying out the thought of the present invention. It is necessary, however, to provide a metal which will be heat conductive in order to take up heat from the shaft of the furnace and permit the air to absorb the heat from said metal. The metallic lining is, of course, constructed of material which will withstand high temperatures and is so formed as to permit expansion and contraction thereof without cracking or fracturing. The air entering the heating chamber takes this heat from the metallic lining, thereby permitting said lining to take up more heat from the shaft of the furnace above the melting zone, and this operation continues during the operation of the furnace. It will be apparent, therefore,

that heat is taken from the shaft of the furnace, thereby reducing the temperature within the shaft of the furnace above the melting zone and preventing the loss of a large amount of the heat units in the fuel above such melting zone. This, it will be apparent, reduces the gas producer effect of the furnace and results in great economy of fuel by reason of the fact that the heat units which are usually lost in the ordinary furnace are conserved and preserved in the fuel until they are delivered to the melting zone. In addition to this, the shaft of the furnace tapers upwardly from the ring 26 and this construction serves to retard the passage of the products of combustion, thereby effecting a substantially complete combustion of the fuel within the shaft.

The diagrammatic Fig. 14 shows the layers of fuel and ore as 86 and 88 respectively, and it will be apparent from an inspection of the figure that some of the layers of fuel in the shaft are adjacent the metallic lining and above the melting zone where the temperature in the furnace is reduced as before-described. The upper layers of fuel, as will be apparent, will have their heat units conserved due to the reduction of temperature in the shaft above the melting zone.

The several sections or rings 26, 28 and 30 may be secured together in many ways, and Figs. 9 to 13 disclose various modifications of such securing means. The general thought which prevails in the several figures is to provide an overlapping of each of the superimposed rings with the ring just beneath, and, referring to Fig. 9, it can be seen that the inner upper edge of the ring 26 is beveled as shown at 90 and the lower inner edge of the ring 28 is correspondingly beveled as at 92 to seat on the bevel 90. The baffle 60 is received and positioned between the uppermost fin of ring 26 and the lowermost fin of ring 28, and said fins are formed into slotted attaching ears 94 at intervals, which ears receive bolts 96 for securing the two rings together, as well as for retaining the baffle 60 in position; the latter being slotted or apertured to take the bolts 96, as will be apparent.

Fig. 10 shows a modification in which the rings 26 and 28 are provided with complementary recesses 98 and 100 respectively, in which is positioned a locking ring 102 whereby the sections are maintained against relative lateral shifting. The baffle 60 is retained between fins on the rings 26 and 28 in this figure in a manner similar to that shown and previously described with respect to Fig. 9. The element 102 is described as a locking ring and said ring also serves as a seal to prevent leakage of the products of combustion between the rings 26 and 28. If desired, the element 102 need not be a continuous ring but may be a relatively short locking key,

a plurality thereof being utilized to maintain the rings 26 and 28 in connected assembled position.

Still another type of connection is shown in Fig. 11 in which the ring 26 is provided with an upwardly extending rib 104 which seats within a recess formed in the lower edge of the ring 28 and thus positions ring 28 on the ring 26. The mounting of the baffle 60 and the securing means for the two rings 26 and 28 is similar to that shown and described in Figs. 9 and 10.

The description just given with regard to Figs. 9, 10 and 11 while specifically mentioning the rings 26 and 28 is, of course, also applicable to the connection of the rings 28 and 30, and this description is to be read with this thought in view.

Fig. 12 discloses a specific mounting of the lower ring 26 on the refractory lining 10, and it can be seen that the upper surface of the lining 10 is adapted to receive a supporting ring 106 provided with an annular recess 108 which takes a depending annular rib 110 formed on the lower wall or bottom of the ring 26; the ring 26 thus being positioned on the supporting ring 106 and centered thereon. The upper end of the ring 26 is provided with an annular rib 112 which is received within an annular recess formed in the lower edge of the ring 28, the rings 26 and 28 thus being mounted one above the other in superimposed relation in such a manner as to prevent relative lateral shifting thereof. The two rings 26 and 28 are connected by means of bolts 100 which also support the baffle 60, in a manner similar to that heretofore described with regard to Figs. 9, 10 and 11.

In Fig. 13, the supporting ring 106 is shown as provided with an annular recess 114 having an undercut wall 116, and the ring 26 is provided with an annular depending supporting flange 118, the inner edge of which is angled or undercut to conform to the shape of the angular wall 116; the flange seating in the recess as shown. A retaining ring 120 is provided for wedging the ring 26 in the recess and also for sealing the connection against leakage. The inner edge of the upper portion of the ring 26 is provided with an undercut recess 122 which receives the lower end of the ring 28, the inner edge of which is undercut as at 124 to seat upon the upper surface of the ring 26, and the latter is provided with an upwardly extending circumferential flange 126 spaced from the ring 28, as clearly shown in said Fig. 13. For preventing relative movement between rings 26 and 28 and also for sealing the joint, a locking ring 128 is provided which is wedgingly received between the flange 126 and the lower end of the ring 28. The rings 120 and 128 are each positively forced into the spaces in which they are seated and the fit of the ring is tight for an obvious purpose. The ele-

115
120
125
130

ments 120 and 128 have been described as rings, but it is to be understood that within the spirit and scope of the invention a plurality of relatively short locking keys may be employed in lieu of a locking ring, the purpose and function of such short keys being the same as the purpose and function of locking rings. The construction disclosed in Fig. 13 is more particularly applicable to the type of ring shown in Figs. 6 and 7 and hereinafter described, but for the sake of uniformity the description of this figure (Fig. 13) has been associated with the description of the remainder of the figures on this particular sheet of drawings which all pertain to the connections of superimposed rings.

It has been found that it is not always necessary to connect the superimposed rings by means of tie rods, as evidenced in Fig. 8, but it is desirable in a furnace of the construction shown wherein the superimposed rings are not connected by tie rods, to position the lowermost ring on a plate 107 which is seated on the upper edge of the refractory lining, as clearly shown in Fig. 15, and which is provided with an inner annular recess 111 for centering the lowermost ring; the rings 26, 28 and 30 thus being centered in spaced relation to the outer casing.

Referring now to Figs. 6 and 7, which figures disclose a modification of the construction of lining rings, it can be seen that the rings which have been designated as 131 and 133 in these figures are superimposed one on the other, and ring 131 is provided with an undercut surface 130 which really defines a depending rib 135 and the upper surface is provided with an annular rib 132; ribs 135 and 132 being adapted to extend into annular recesses formed in the supporting plate 142 and the lower end of the superposed ring 133, respectively. Each of said rings comprises a plurality of arcuate segments 134, shown clearly in Fig. 6. The segments 134 are corrugated as at 136, and the ends of adjacent sections are provided with complementary recesses which receive locking pins 138 for tying the several sections of the rings together in an obvious manner. To prevent accidental displacement of the superimposed rings, tie rods 140 are employed which extend through a supporting plate 142 mounted on and supported by an angle 144 secured to the sheathing in any suitable or desired manner and which may be embedded in the refractory lining 10.

From the above description, it is believed the operation of the present invention will be fully apparent to those skilled in the art, but it is desired to state that when air is admitted through the intake into the heating chamber the air will pass from the chamber through the conduit from where it will be delivered into the air belt and then to the tuyères; the air in its passage through

the heating chamber being intensely and uniformly heated as before described. Attention is called to the fact that the shaft of the furnace tapers upwardly from the lowermost ring 26 to the top of the furnace; all of the rings in the shaft being of successively decreasing diameter, and this results in a choking of combustion within the furnace, thus effecting complete combustion of the fuel therein and a consequent saving thereof and a distinctly more efficient operation of the furnace. Further, and as before-mentioned, the provision or substitution of the metallic lining within the furnace for a portion of the usual refractory lining serves to effect a reduction in temperature in the furnace shaft above the melting zone, thereby reducing the gas producer effect of the entire furnace and a resulting preservation of the heat units in the fuel until the latter reaches the melting zone, thus affording a greater ratio of fuel than has been heretofore known.

Attention is called to applicant's construction of furnace in that there have been provided really three distinct zones in the furnace: the first zone I term the melting zone which is just above the tuyères; the second zone is what I term the preheating zone and extends from the melting zone upwardly to about the upper edge of the refractory lining and wherein the alternate fuel and ore beds are preheated until they reach the melting zone; and the third zone I term the magazine, said zone being that encompassed by the metallic lining and wherein the fuel beds and ore beds are maintained at a reduced temperature whereby the heat units in the fuel beds are conserved preventing loss thereof.

What is claimed is:

1. In a cupola furnace having an outer sheathing, refractory lining at the lower portion of the sheathing, and a plurality of superposed internally ribbed metallic rings of successively decreased diameter supported by the refractory lining and arranged in spaced relation to the sheathing to provide an air heating chamber, the contacting surfaces of adjacent rings being so formed as to be interfitting whereby to permit individual expansion of said rings, and detachable means for securing the rings together.

2. A cupola furnace having an outer casing, a refractory lining at the lower end of the casing, and a metallic lining in the upper portion of the casing arranged in spaced relation to the casing and defining with the casing a heating chamber, said lining being formed of connected segments, and means between adjacent segment ends and contacting therewith for retaining said segments in assembled relation.

3. A cupola furnace having as a portion of the lining thereof a plurality of metallic rings interfittingly connected together in superposed relation whereby to permit indi-

- vidual expansion thereof, and an outer sheathing, the inner surface of said rings being vertically ribbed and the outer surface of said rings being laterally ribbed and spaced 5 from the sheathing of the furnace to provide an air heating chamber.
4. In a cupola furnace, the combination with a sheathing and refractory lining adjacent the lower end thereof, of a metallic lining supported by the refractory lining and comprising a plurality of superimposed metallic rings of successively decreasing diameter interfittingly connected together to permit individual expansion of said rings 10 and having their outer walls spaced from said sheathing to define an air chamber.
5. In a cupola furnace, an outer sheathing, refractory lining material adjacent the lower end of the sheathing, a supporting element carried by the refractory material, a plurality of superposed metallic rings supported by the supporting element, the lowermost of which is centered on the supporting element and the upper rings being connected together 15 in interfitting relation, and tie rods for retaining said rings in connected relation.
6. In a cupola furnace, an outer casing, a plurality of superposed metallic rings forming the lining of the furnace shaft above the 20 melting zone thereof and defining with the outer casing a chamber for receiving air to be heated by heat absorbed by the metallic lining from the adjacent portion of the furnace shaft whereby to reduce the temperature in the shaft adjacent the metallic lining, and means extending between the upper and lower rings to retain the metallic lining in assembled relation.
7. A cupola furnace comprising a shaft, 25 an outer sheathing, a metallic member at the upper end of the shaft and extending adjacent the charging doors thereof and forming a part only of the lining of the shaft, said member being formed of a plurality of overlappingly connected superposed rings with upper rings overlapping the lower rings whereby to permit expansion of the lower rings relative to the upper rings under the influence of heat.
8. In a cupola furnace, an outer sheathing, 30 a refractory liner at the lower end of the furnace having its upper end circumferentially recessed, a supporting element mounted on the upper edge of the refractory liner, a metallic liner supported on the supporting element and positioned by the circumferential recess, said liner defining, with the outer sheathing, a heating chamber for air, a sealing plate for closing the upper end of the heating chamber and tie-rods in the heating chamber extending between the supporting element and sealing plate for retaining the metallic liner in position.
9. In a cupola furnace, an outer sheathing, 35 a refractory liner at the lower end of the
- furnace and having a recessed upper edge, a metallic liner supported by the refractory liner and defining, with the outer sheathing, an air heating chamber, said liner comprising a lower ring supported in the recess in 70 said refractory liner and upper rings supported by said lower ring, a sealing plate between the sheathing and uppermost rings to close the upper end of the heating chamber, and tie-rods connected between the lower and 75 uppermost rings for retaining the liner rings in assembled position.
10. In a cupola furnace, an outer sheathing, a refractory liner at the lower end of the furnace, an annular support on the upper 80 surface of the refractory liner, a metal liner supported by said support and comprising a plurality of superposed rings interfittingly connected for permitting individual expansion of said rings and defining with the 85 sheathing a chamber receiving atmospheric air to be heated by heat from the furnace shaft absorbed by said metal liner, a sealing plate closing the upper end of said chamber, and means in the heating chamber engaging 90 the metal liner for retaining the latter in assembled position.
11. A cupola furnace having as a portion of the lining thereof a plurality of metallic rings interfittingly connected together in superimposed relation whereby to permit individual expansion thereof. 95
12. A cupola furnace having as a portion of the lining thereof a plurality of superposed metallic rings interfittingly connected together to permit individual expansion thereof and each formed of a plurality of connected segments. 100
13. In a cupola furnace, a metallic member as a part of the furnace lining and defining one wall of an air heating chamber, said liner comprising a plurality of segments arranged end to end to define a ring, and means between adjacent ends and contacting therewith for retaining said segments in assembled relation. 105
14. A cupola furnace having as a portion of the lining thereof a metallic ring formed of a plurality of segments, and connecting elements between adjacent segment ends and held thereby for connecting the segments together and for retaining them in assembled position. 110
15. A cupola furnace having as a portion of the lining thereof a metallic ring formed of a plurality of segments, and connecting means at the juncture of adjacent segment ends and held in position thereby for connecting the segments together and for retaining them in assembled position. 115
16. In a cupola furnace, an outer sheathing, and a metallic member forming a part of the furnace lining and defining one wall of an air heating chamber, said metallic member comprising a plurality of segments ar. 120
- 125
- 130

ranged end to end to define a ring, and connecting means independent of the sheathing arranged at the juncture of adjacent segment ends and held in position thereby for connecting the segments together and for retaining them in assembled position.

5 In witness whereof I have hereunto set my hand.

FREDERICK A. STEVENSON.
